RAILWAY SIGNALING APPARATUS

Henry S. Young, Wilkinsburg, Pa., assignor to
The Union Switch & Signal Company, Swiss-
vale, Pa., a corporation of Pennsylvania

Application January 7, 1941, Serial No. 373,432

4 Claims. (Cl. 246—33)

My invention relates to railway signaling apparatus, and it has particular reference to the organization of such apparatus into railway signaling systems of the class wherein railway signals are controlled to govern the movement of traffic in both directions on a single track railroad. More particularly, my invention relates to the organization of apparatus into railway signal systems of the absolute permissive block signal class.

Absolute permissive block (APB) signal systems are employed generally on single track railroads to govern traffic between two successive passing sidings, and are arranged in such manner that when a train enters the stretch between the sidings, all of the opposing signals in the stretch up to the next siding are set to stop, while the signals in the rear of the train as it proceeds between the sidings are successively cleared to permit a second train to follow the first at the usual following distance. In such systems, it has been customary to utilize both track circuit and line wire control; and to provide the necessary directional control established when a train enters the stretch between sidings, it has been customary to employ two line wires one for each direction, and either two separate return wires one for each control wire, or a single return wire common to both control wires.

It is an object of my present invention to provide a novel and improved signal system in which a two wire line circuit is utilized together with the customary track circuit control to provide a novel and improved absolute permissive block signal system of signaling.

Another object is to provide a signal system in which a two wire line circuit is utilized to control opposing signals to provide an absolute permissive block signal system.

An additional object is to organize signaling apparatus into a novel and improved absolute permissive block signal system wherein a double wire, double break control of two opposing signals is effected utilizing only a two wire line circuit for controlling the two opposing signals.

A further object is to organize signaling apparatus into a novel and improved absolute permissive block signal system wherein selective control of opposing signals is effected by supplying two distinctively characterized control currents to a two wire line circuit.

Another object is to organize railway signal apparatus into a novel and improved absolute permissive block signal system in which the num-

ber of line wires required is reduced to a minimum.

An additional object of my invention is to organize railway signalizing apparatus into novel and improved absolute permissive block signal systems of signaling.

The above-mentioned and other important objects and characteristic features of my invention which will become readily apparent from the following description, are attained in accordance with my invention by utilizing control means responsive only to current having certain characteristics for controlling one set of signals spaced along a track and governing traffic in one direction, and utilizing other control means responsive only to current having distinctively different characteristics for controlling an opposing set of signals spaced along the track and governing traffic in the other direction. The two control means for each pair of opposing signals are governed by a two wire line circuit supplied with each of the two distinctively characterized currents, and track circuit control of such line circuit is provided to establish directional control of the opposing signals in the manner customary in absolute permissive block signal systems. In addition, the track circuit control is arranged to break both wires of the two wire line circuit so as to obtain a double wire, double break control for each signal; and means is provided for preventing the opposing signal in the rear of a train from clearing as the train proceeds along the stretch.

Other important features of my invention reside in the particular arrangement of apparatus and organization of circuits employed. I shall describe a preferred form of apparatus embodying my invention, and shall then point out the novel features of my invention in claims.

In the accompanying drawings, Figs. 1a and 1b are diagrammatic views which when placed end to end with Fig. 1a on the left, represent a preferred form of apparatus embodying my invention. Referring to the drawing, the reference character X designates a stretch of single track railroad connected with successive passing sidings L and M by switches which are designated by the reference character W with distinguishing suffixes. Although only one end of siding L is shown in the drawings, it is to be understood that both ends of this siding are connected with the stretch similarly to siding M.

The rails 1 and 1a of track X are divided in the customary manner by insulated joints 2 into a plurality of successive adjoining track sections

D—E, E—F, F—H and H—J. Section D—E is further divided by insulated joints 2 into subsections D—Da and Da—E, and section F—H likewise is divided by insulated joints 2 into subsections F—Fa and Fa—H. Siding M is connected by switches W2 and W3 with section H—J, which section will be referred to hereinafter as a "siding" section. Sections D—E, E—F and F—H are between siding section H—J and the section with which siding L is connected, and therefore will be referred to hereinafter as "intermediate" sections.

Section H—J and subsections D—Da, Da—E, F—Fa and Fa—H are provided with track circuits each of which comprises a track relay, designated by the reference character TR with a suitably distinguishing prefix, connected across the rails at one end of the section or subsection, as the case may be, and a suitable source of track circuit current connected across the other end. As shown in the drawing, alternating current sources of track circuit current are utilized, each comprising a track transformer, designated by the reference characters TT with a suitably distinguishing prefix, having a secondary winding 5 connected to the rails of the associated section or subsection, and having a primary winding 6 connected to a suitable source of alternating current, such as a generator not shown but having its two terminals represented in the drawing by the reference characters BX and CX.

The track relays TR, as shown, are alternating current relays having a local winding constantly supplied with alternating current from the source of alternating current, represented by terminals BX and CX, and having a track winding connected to the rails of the associated section or subsection. These relays are constructed in a manner well known so as to operate their associated armatures to a picked-up position when and only when both the local and track windings are energized.

Section E—F also is provided with a track circuit comprising a track relay 5TR connected to one end of the section and a track transformer 5TT having a secondary winding 5 connected to the rails adjacent the other end. The primary winding 6 of transformer 5TT is constantly supplied with alternating current, and a portion of the current induced in secondary winding 5 of the transformer and supplied to the rails of section E—F normally energizes a single element alternating current track relay 5ATR connected to the rails of the section intermediate the point at which secondary winding 5 of transformer 5TT is connected, and the adjacent end F of the section.

The reference characters S with suitably distinguishing prefixes, designate signals for governing traffic on track X. Two of such signals, one governing traffic in one direction and the other governing traffic in the opposite direction, are located adjacent each pair of insulated joints defining track sections D—E, E—F, etc. Signals bearing an odd-numbered prefix, such as 3, 5, etc., in their reference characters are arranged to govern eastbound traffic, that is, traffic operating on track X from left to right as viewed in the drawings. The other signals having even-numbered prefixes before their reference characters are disposed to govern westbound traffic. These signals may be of any suitable form, such as position light, color light, searchlight, etc., but each is represented in the drawing as a color light signal having a green lamp G, a yellow lamp Y

and a red lamp R, which lamps when illuminated indicate high-speed, reduced-speed and stop, respectively. The high-speed and reduced-speed indications will be referred to hereinafter as "clear" and "caution" indications, respectively.

Signals 3S and 8S governing the entrance of eastbound and westbound trains, respectively, into stretch X preferably are provided with suitable number plates, marker lights, or a combination of both to indicate that these signals are headblock signals. As shown, such signals are indicated to be headblock signals by providing each of these signals with two red lamps R, both energized in multiple when the signal is conditioned to display its stop aspect.

Signals 2S and 9S governing the entrance of westbound and eastbound trains, respectively, into the siding sections, I shall refer to hereinafter as "entering" signals. The other signals disposed intermediate headblock signals 3S and 8S, and entering signals 2S and 9S, I shall refer to hereinafter as "intermediate" signals.

Associated with each signal S there is a polarized signal control relay, designated by the reference character HDR with a prefix corresponding to the prefix of the associated signal. The signal control relays HDR associated with the set of westbound signals are arranged to respond only to current having certain characteristics, while those associated with the opposing set of eastbound signals are arranged to respond only to current having distinctively different characteristics. For the purposes of this description, I shall assume that the two distinctively characterized currents are supplied respectively from a source of alternating current and a source of unidirectional current. I shall further assume that the HDR control relays associated with the westbound signals are alternating current relays responsive only to alternating current and that the HDR control relays associated with the eastbound signals are unidirectional relays and respond only to unidirectional current.

Associated with each signal control relay HDR there is a slow acting repeater relay, designated by the reference character HDPR with a prefix corresponding to the prefix employed in the reference character of its associated control relay. Each repeater relay associated with a direct current polarized signal control relay, such as relay 3HDR, is energized over an obvious circuit including a front contact of its associated signal control relay. For example, relay 3HDPR associated with relay 3HDR is energized over a circuit which extends from one terminal B of a suitable source of direct current, such as a battery not shown, through front contact 12 of relay 3HDR and the winding of relay 3HDPR to the other terminal N of the source of current. Each repeater relay associated with an alternating current polarized signal control relay, such as relay 4HDR is energized over an obvious circuit including either a normal or a reverse polar contact of its associated polarized signal control relay. Relay 4HDPR is energized, for example, over a circuit extending from terminal B through contact 13 closed in the normal or reverse position of relay 4HDR, and the winding of relay 4HDPR to terminal N.

Each signal control relay HDR cooperates with its associated repeater relay HDPR in controlling the associated signal S in such manner that when the signal control relay is energized in its normal direction to operate its polar contact member 16 to its normal or left-hand position, as viewed in

the drawings, the associated signal is controlled to display its proceed indication; when the signal control relay is energized with current of reverse polarity and operates its polar contact member 16 to the reverse position, the associated signal is controlled to display its caution indication; and when the signal control relay and its repeater relay are deenergized, the associated signal is controlled to display its stop indication. For example, when polarized signal control relay 3HDR is energized in its normal direction, relay 3HDPR is energized and lamp G of signal 3S is illuminated by current supplied over a circuit extending from terminal BX through front contact 14 of relay 3HDPR, front contact 15 and polar contact 16 closed in the normal or left-hand position of relay 3HDR, and the filament of lamp G of signal 3S to terminal CX. When relay 3HDR is energized in its reverse direction, polar contact member 16 is operated to its right-hand position to open the previously traced circuit of lamp G, and a reverse polar contact of relay 3HDR is closed to complete an obvious circuit for lamp Y of signal 3S. When relay 3HDR is deenergized, its front contact 12 is opened to in turn deenergize relay 3HDPR so that back contact 14 of relay 3HDPR is closed to complete an obvious energizing circuit for lamps R of signal 3S.

Associated with each intermediate signal 4S, 5S, 6S and 7S there is a directional control stick relay, designated by the reference character SR with a distinguishing prefix corresponding to the prefix of the associated signal. Each stick relay normally is deenergized, and becomes picked up when the section governed by the associated signal becomes occupied provided that the opposite intermediate signal is set to stop. That is to say, when section E-F becomes occupied by an eastbound train so that relay 5TR drops, relay 5SR associated with signal 5S picks up provided that relay 4HDPR is released to control the opposite intermediate signal 4S to stop. A pick-up circuit for relay 5SR, completed under the assumed conditions, may be traced from terminal B through back contact 80 of relay 4HDPR, back contact 81 of relay 5TR, front contact 82 of relay 5HDPR and the winding of relay 5SR to terminal N. Each stick relay when picked up completes a holding circuit which is effective to hold such relay energized until the train vacates the section next in advance of the section governed by the associated signal.

Overlap control means is provided for each intermediate section adjacent a siding section. An overlap control relay 2DPR is provided for section D-E adjacent siding L; an overlap control relay 10DPR is provided for the intermediate section immediately to the east of siding section H-J; and overlap control for section F-H adjacent siding M, is provided by utilizing polar contact members of signal control relay 9HDR, as will be made clear presently.

Each of the switches W operates a first contact 18 and a second contact 19, which contacts are closed only when the respective switch is in its normal position, that is, the position for directing traffic over stretch X only and not to or from its passing siding. In order to simplify the drawings, I have omitted showing the mechanisms which cause operation of switches W to take place, it being understood that such switches may be manually and/or power operated by suitable mechanisms well known in the art.

Each two opposing signals governing traffic over a section are controlled by a two wire line circuit which extends from one end of the section to the other, and by two sources of current, one connected to one end of the line circuit and the other connected to the other end. The two sources of current connected to each line circuit include a source of alternating current, represented in the drawings as a transformer designated by the reference character LT with a suitably distinguishing prefix, having a primary winding 20 connected to the source of alternating current and a secondary winding 21 connected to one end of the associated line circuit; and a source of unidirectional current, which latter source may be a battery but which is represented in the drawings as a full-wave rectifier, designated by the reference character LR with a distinguishing prefix, having its input terminals connected through a transformer to a source of alternating current and having its output terminals connected to the other end of the associated line circuit. Each source is connected to its associated line circuit at the end of the section opposite that at which is located the signal controlled by the polarized relay responsive only to that form of current. That is to say, the signal control relays associated with the eastbound signals, such as signal control relays 3HDR, 5HDR, etc., as stated previously are responsive only to direct current. In accordance with the usual custom, relay 3HDR, for example, is located adjacent the associated signal 3S positioned adjacent end D of section D-E, hence rectifier 3LR is connected to the line circuit of section D-E at the opposite end E of the section. Transformer 4LT is of course, connected to the line circuit of section D-E at the left-hand end D, for controlling relay 4HDR positioned adjacent and controlling signal 4S located at end E of the section.

In order to simplify the drawings, I have represented contacts of relays at times disposed remote from the relays operating such contacts, but in each case each of such contacts has been represented in the normal condition which it assumes and has been identified not only by a reference character individual to such contact, but also by placing immediately above such contact the reference character of the relay causing that contact to operate. For example, the reference character 2DPR has been placed immediately above contact 23 to indicate that this contact is operated by relay 2DPR, and the contact is represented in a closed front position to indicate that such relay is normally energized.

As represented in the drawings, the apparatus embodying my invention is in its normal condition, that is, each section D-E, E-F, F-H, H-J is unoccupied; each switch W is in its normal position; each signal S is indicating proceed; each intermediate section (not shown) between section H-J and the next siding to the east of siding M is unoccupied; and each section (not shown) between section D-E and the next siding west of siding L is unoccupied. With these various sections mentioned unoccupied, the track relays TR shown in the drawings are energized, and overlap relay 2DPR is energized.

Each signal control relay HDR also is energized by current of what I shall term normal polarity, and consequently operates its polar contact members to their left-hand or normal positions so as to control the associated signal to its clear indi-

cation. For example, signal control relays 3HDR and 4HDR, controlling opposing signals 3S and 4S, respectively, are energized over a two wire line circuit which may be traced from the left-hand terminal, as viewed in the drawing, of secondary winding 21 of transformer 4LT, through resistor 24, front contact 23 of overlap relay 2DPR, front contact 25 of relay 3TR of subsection D—Da, line wire 26, front contact 27 of relay 4TR of subsection Da—E, front contact 28 of signal control repeater relay 5HDPR associated with signal 5S, reactor 29, rectifier 3LR, front contact 30 of relay 5HDPR, front contact 31 of relay 4TR, line wire 32, front contact 33 of relay 3TR, and front contact 34 of relay 2DPR to the other or right-hand terminal of winding 21 of transformer 4LT. The control winding of relay 4HDR is connected through back contact 35 of stick relay 5SR and front contact 27 of relay 4TR to line wire 26 of the above traced circuit and is connected through a resistor 36 and front contact 31 of relay 4TR to lower line wire 32. The polarity of current supplied from transformer 4LT to relay 4HDR is controlled by overlap relay 2DPR, which relay is effective when energized to close its front contacts 23 and 34 to condition, when relays 3TR and 4TR are also energized, the line circuit to supply relay 4HDR with alternating current having one relative instantaneous polarity which I shall term normal polarity, but which relay 2DPR when released closes its back contacts 23 and 34 to thereby reverse the polarity of current supplied to relay 4HDR, as is readily apparent from an inspection of the drawings.

Relay 3HDR is connected, as is readily apparent from an inspection of the drawings, through front contact 25 of relay 3TR to line wire 26 of the line circuit of section D—E, and is connected through front contact 33 of relay 3TR to line wire 32. The relative polarity of current supplied from rectifier 3LR to relay 3HDR is controlled by relay 5HDPR, which relay when energized closes its front contacts 28 and 30 and conditions the line circuit to supply current of one relative polarity, which I shall term normal polarity, to relay 3HDR, and which relay 5HDPR when released closes its back contacts 28 and 30 to reverse the polarity of current supplied to relay 3HDR, provided that relay 5SR is picked up to close its front contact 35. In the event that relay 5SR is released when relay 5HDPR is released, then the circuit of relay 3HDR is opened, as can be seen from an inspection of the drawings.

The line circuit of section E—F, controlling the energization of relays 5HDR and 6HDR, is substantially similar to the line circuit just traced for section D—E, with the exception that a back contact 37 of stick relay 4SR is interposed in the connection of relay 5HDR to line wire 26 of the line circuit of section E—F, and front contact 31 of relay 4SR is interposed in the connection of back contact 40 of relay 4HDPR to line wire 26.

The line circuit of section F—H, controlling the energization of relays 7HDR and 8HDR, also is substantially similar to the line circuit previously traced for section D—E, with the exception that relay 7HDR is connected through back contact 60 of relay 6SR and front contact 51 of relay 7TR to the upper line wire 26 of that line circuit; the other control relay 8HDR is connected to the line wires directly without the interposition of a contact of a stick relay SR; and polar contact members 53 and 56 of relay 9HDR are interposed in the line circuit to pole change

the current supplied from rectifier 7LR to relay 7HDR, as is readily apparent from an inspection of the drawing. These pole changing polar contact members of relay 9HDR function to provide overlap control of signal 7S in a manner to be explained presently.

The line circuit controlling the energization of relays 9HDR and 10HDR, is also similar to the line circuit of section D—E, except that contacts 18 and 19 of switch W2, and contacts 18 and 19 of switch W3, are interposed in the line circuit of section H—J, as is readily apparent from an inspection of the drawings. Furthermore, both relays 9HDR and 10HDR are connected to the line circuit without the interposition of contacts of the previously mentioned stick relays SR.

With the signal control relays HDR all energized by current of normal polarity, all repeater relays HDPR are energized; all signals S are controlled to display their respective clear indication; and all stick relays SR are released.

I shall now assume that an eastbound train enters the first intermediate section (not shown) east of the first siding west of the section with which siding L is connected. Relay 2HDR is thereby caused to reverse its polar contact members in substantially the same manner as relay 10HDR is caused to shift its polar contact members when the eastbound train enters section D—E, as will be explained presently, and signal 2S accordingly is caused to display its caution indication over an obvious circuit passing from terminal BX through front contact 14 of relay 2HDPR, polar contact member 16 of relay 2HDR in its reverse position and the filament of lamp Y of signal 2S to terminal CX. Overlap relay 2DPR, which is energized over normal contact 11 of relay 2HDR, also is caused to release, with the result that its front contacts 23 and 34 open and its back contacts 23 and 34 close to reverse the polarity of energization of relay 4HDR in a manner readily apparent from an inspection of the drawing, and signal 4S thereupon is controlled to its caution indication over an obvious circuit similar to that just traced for lamp Y of signal 2S. This condition of the apparatus is maintained until the train enters the section immediately to the west of section D—E, whereupon relay 2TR associated with such section releases to cause the release of relay 2HDR. Relay 2HDPR also releases when the polar contact members of relay 2HDR assume their deenergized or mid positions and signal 2S accordingly is controlled to display its stop indication when back contact 14 of relay 2HDPR closes to complete an obvious circuit for lamp R of that signal.

When the train enters the first intermediate section, D—E, between passing sidings L and M, all signals governing traffic in the opposite, or westbound, direction between the sidings are set to stop, and the eastbound signal 3S associated with the section entered also is set to stop. The two opposing signals 3S and 4S governing traffic in section D—E assume their respective stop conditions due to the deenergization of relays 3HDR and 4HDR caused by the opening of the associated line circuit when front contacts 25 and 33 of relay 3TR open when the latter relay releases in response to the train in subsection D—Da, signal 3S being controlled to its stop indication when back contact 14 of repeater relay 3HDPR closes due to the interruption of the energizing circuit of relay 3HDPR when relay 3HDR releases, while signal 4S is controlled to its stop condition over a circuit completed over back

contact 14 of relay 4HDPR, which latter relay releases in response to the release of relay 4HDR.

The releasing of relay 4HDPR and consequent opening of its contacts 40 and 45 disconnects transformer 6LT from the line circuit of section E—F, as is readily apparent from an inspection of the drawings, and relay 6HDR controlled by alternating current supplied to the line circuit of section E—F accordingly releases to cause the release in turn of relay 6HDPR. When back contact 14 of relay 6HDPR closes, signal 6S is controlled to display its stop indication, and when front contacts 50 and 59 of relay 6HDPR open, transformer 8LT is disconnected from the line circuit of section F—H, with the result that relay 8HDR is caused to release. Relay 8HDPR thereupon releases to close its back contact 14 and control signal 8S to its stop condition, and back contacts 64 and 73 of relay 8HDPR close to reverse the polarity of alternating current supplied from transformer 10LT to relay 10HDR, as is readily apparent from an inspection of the drawing. Relay 10HDR accordingly reverses its polar contact members, thereby causing overlap relay 10DPR to release and signal 10S to assume its caution indication, in a manner similar to that mentioned hereinbefore in connection with the reversal of the polar contact members of relay 2HDR when the train enters the first intermediate section east of the first siding west of siding L.

When the train enters subsection Da—E, relay 4TR releases to open its front contacts 27 and 31 interposed in the line circuit of section D—E, but the releasing of relay 4TR at this time does not affect the condition of the apparatus previously described. If the train is relatively short, it will vacate the section to the west of section D—E prior to entering section E—F, and when the section west of section D—E becomes vacated, relay 2TR picks up to close its front contacts interposed in the line circuit of such section to condition relay 2HDR to be energized in its normal direction in a manner similar to that herein-after to be explained in detail in connection with relay 10HDR when section H—J becomes vacated. The energization of relay 2HDR at normal polarity causes relays 2DPR and 2HDPR to be energized, the latter relay in turn completing the previously traced energizing circuit of lamp G of signal 2S to cause that signal to display its clear indication. The eastbound apparatus associated with the section immediately to the west of section D—E is not at this time restored to its normal condition, however, since with the train in subsection D—Da, relay 3TR is released and holds open its front contacts interposed in the line circuit of the section west of section D—E, and back contacts of relay 3HDPR, interposed in the same circuit, are also closed. When relay 3TR picks up upon the train vacating subsection D—Da, its front contacts interposed in the line circuit of the section to the west of section D—E, and contacts 25 and 33 interposed in the line circuit of section D—E, become closed, but the line circuit of section D—E is held open at front contacts 27 and 31 of relay 4TR.

When the train enters section E—F, relay 5TR is first shunted and releases to open its front contacts 41 and 45 interposed in the line circuit of section E—F. Relay 5HDR thereupon is deenergized and releases to open its front contact 12 and thereby open the energizing circuit of its repeater relay 5HDPR, but prior to the release

of relay 5HDPR, that is, during the slow release interval of such relay, stick relay 5SR becomes energized over a circuit extending from terminal B through back contact 80 of relay 4HDPR, back contact 81 of relay 5TR, front contact 82 of relay 5HDPR and the winding of relay 5SR to terminal N. Relay 5SR accordingly picks up to close its front stick contact 83, thereby preparing a stick circuit which becomes completed 10 when back contact 82 of relay 5HDPR closes at the end of its slow release interval, this stick circuit extending from terminal B through back contact 82 of relay 5HDPR, front contact 83 of relay 5SR and the winding of relay 5SR to terminal N. The energization of relay 5SR also causes its front contact 35 to become closed, thereby preparing an alternate path in the line circuit of section D—E, which alternate path will be referred to presently.

20 Signal 5S of course assumes its stop condition when relays 5HDPR and 5HDR release, thereby indicating that section E—F is occupied.

If, now, the train vacates subsection Da—E, relay 4TR picks up and closes its front contacts 27 and 31 with the result that current of reverse polarity is supplied to relay 3HDR over a circuit extending from the upper or positive terminal of rectifier 3LR through reactor 29, back contact 28 of relay 5HDPR, front contact 31 of relay 4TR, line wire 32, front contact 33 of relay 3TR, the winding of relay 3HDR, front contact 25 of relay 3TR, line wire 26, front contact 27 of relay 4TR, front contact 35 of relay 5SR, and back contact 30 of relay 5HDPR to the lower or negative terminal of rectifier 3LR. Relay 3HDR accordingly reverses its polar contact members and closes its front contact 12 to reenergize relay 3HDPR, whereupon lamp Y of signal 3S becomes energized over a circuit extending from terminal BX through front contact 14 of relay 3HDPR, front contact 15 and polar contact 16 of relay 3HDR in its reverse position, and the filament of lamp Y of signal 3S to terminal CX.

The energization of relay 4TR does not at this time cause relay 4HDR to become reenergized, since with relay 5SR energized, back contact 35 of relay 5SR is opened to disconnect relay 4HDR from the line circuit of section D—E. Relay 4HDR accordingly remains released and signal 4S continues to display its stop aspect. It follows, therefore, that the opposing signal governing traffic in the section next in the rear of an occupied section is prevented from clearing and is held at its stop condition, whereas the signal governing following movements in the section next in the rear of an occupied section is controlled to its caution indication to permit following moves at the customary following distance.

As the train approaches right-hand end F of section E—F, relay 5ATR is shunted and releases to open its front contact 42 interposed in the line circuit of section E—F, and when the train enters section F—H, relay 7TR associated with subsection F—Fa is first shunted and releases to open its front contacts 51 and 58 interposed in the line circuit of section F—H. Relay 7HDR thereupon becomes deenergized and releases to open its front contact 12 to open the energizing circuit of relay 7HDPR, but prior to the release of the latter relay, which of course sets signal 7S to stop, relay 7SR becomes energized over a circuit extending from terminal B through back contact 85 of relay 6HDPR, back contact 86 of relay 7TR, front contact 87 of relay 7HDPR, and the winding of relay 7SR to

terminal N. Relay 7SR accordingly picks up to close its stick front contact 88 to prepare its stick circuit, which circuit becomes completed when back contact 87 of relay 7HDPR closes at the end of a slow release interval of that relay. Relay 7SR also closes its front contact 47 to prepare an alternate path in the line circuit of section E—F, this alternate path being effective when relays 5TR and 5ATR pick up as the rear of the train vacates section E—F, to condition current of reverse polarity to be supplied over back contacts 43 and 44 of relay 7HDPR to relay 5HDR, which latter relay accordingly becomes energized to swing its polar contact members to their reverse positions, and to close its front contact 12 and thereby reenergize relay 5HDPR. When relay 5HDPR picks up at the end of its slow pick-up period, signal 5S is controlled to its caution indication over an obvious circuit including front contact 14 of relay 5HDPR and front contact 15 and polar contact 16 of relay 5HDR in its reverse position; front contacts 28 and 30 of relay 5HDPR interposed in the previously traced normal line circuit of section D—E become closed; and the previously traced stick circuit of relay 5SR is interrupted at back contact 82 of relay 5HDPR so that relay 5SR releases to close its back contact 35 and reconnect relay 4HDR to the line circuit of section D—E. Relays 3HDR and 4HDR thereupon become energized by current of normal polarity; relay 4HDPR becomes energized; and signals 3S and 4S are controlled to their respective clear indications.

When the train enters subsection Fa—H, relay 8TR becomes shunted and releases to open its front contacts 52 and 57 interposed in the line circuit of the associated section, and front contacts 65 and 72 interposed in the line circuit of section H—J, thereby deenergizing relay 10HDR, which latter relay releases to cause the release in turn of overlap relay 10DPR and repeater relay 10HDPR. When relay 10HDPR releases, signal 10S is controlled to its stop indication.

Relay 7TR picks up when the train vacates subsection F—Fa. Then, when the train enters siding section H—J, relay 9TR releases to open its front contacts 66 and 71 and thereby open the circuit of relay 9HDR, which relay accordingly releases to cause in turn the release of relay 9HDPR, thereby controlling signal 9S to its stop indication. Relay 9HDPR also closes its back contacts 54 and 55 interposed in the line circuit of section F—H, to condition current of reverse polarity to be supplied to relay 7HDR when relay 8TR picks up to close its front contacts 52 and 57 when the train vacates section F—H.

The energization of relay 7HDR by current of reverse polarity causes its polar contact members to be operated to their reverse positions, and causes its front contact 12 to be closed to reenergize repeater relay 7HDPR. When relay 7HDPR picks up, signal 7S is controlled to its caution indication; front contacts 43 and 44 of relay 7HDPR, interposed in the line circuit of section E—F, become closed; back contact 87 of relay 7HDPR opens to open the previously mentioned stick circuit of relay 7SR whereupon the latter releases to close its back contact 47 and reconnect relay 6HDR to the line circuit of section E—F; relays 5HDR and 6HDR become energized by current of normal polarity; relay 6HDPR is reenergized and picked up, and signals 5S and 6S are both controlled to their normal clear condition.

Relay 8HDR also becomes energized when relay

8TR picks up, the current supplied to relay 8HDR however being of normal polarity so that when repeater relay 8HDPR becomes reenergized, signal 8S is controlled to its clear condition.

When the train vacates section H—J and relay 9TR picks up, relay 10HDR becomes energized by current of normal polarity and operates its polar contact members to their normal position to cause relays 10DPR and 10HDPR in turn to pick up. When relay 10HDPR picks up, signal 10S is cleared, but signal 9S remains in its stop condition since the circuit of relay 9HDR is open at front contacts 67 and 70 of relay 10TR, associated with the section immediately to the east of section H—J. When relay 10TR picks up, current of reverse polarity first is supplied to relay 9HDR over back contacts 68 and 69 of relay 11HDPR (the signal control repeater relay, not shown, of signal 11S) so that relay 9HDR operates its polar contact members to their reverse positions, and closes its front contact 12 to reenergize repeater relay 9HDPR. When relay 9HDPR picks up to close its front contact 14, signal 9S is controlled to its caution condition; and when front contacts 54 and 55 of relay 9HDPR close, current of reverse polarity is supplied to relay 7HDR over contact members 53 and 56 of relay 7HDR in their reverse positions. Relay 7HDR accordingly retains its polar contact members in their reverse positions to retain signal 7S at its caution indication. When, however, relay 11HDPR picks up to close its front contacts 68 and 69, current of normal polarity is supplied to relay 9HDR so that signal 9S is controlled to its clear condition, and polar contact members 53 and 56 are operated to their normal positions so that current of normal polarity is supplied to relay 7HDR and as a result signal 7S also is controlled to its clear condition.

It is believed that the operation of the apparatus embodying my invention for a westbound train will be readily apparent from an inspection of the drawing and from the foregoing description of the operation of the apparatus for an eastbound train, and further detailed explanation is deemed unnecessary except to point out that when the westbound train enters the first intermediate section west of the first siding east of section H—J, relay 9HDR is caused to operate its polar contact members to their reverse positions, thereby controlling signal 9S to its caution indication, due to the polarity of energization of relay 9HDR being reversed in a manner substantially similar to that pointed out whereby the polarity of energization of relay 10HDR is reversed when an eastbound train enters section D—E. The reversal of the polar contact members 53 and 56 of relay 9HDR of course causes the polarity of energization of relay 7HDR to be reversed, thereby causing signal 7S to be controlled to its caution indication and providing overlap control for signal 7S.

In addition, it should be pointed out that when a westbound train operates between sidings M and L, the stick relays SR associated with the westbound signals 6 and 4 are caused to be energized to hold the opposing signals 7S and 5S at stop when the train occupies the section next in advance of the section governed by such opposing signals.

From the foregoing description, it is readily apparent that I have provided a novel and improved arrangement whereby an absolute permissive block signal system of signaling is provided and in which only two line wires are re-

quired for controlling each pair of opposing signals. In addition, it is evident that the track circuit control of the two line wires is effective to open both wires, thereby providing maximum assurance against crosses and/or grounds and providing a double wire, double break system of control.

Although I have herein shown and described only one form of railway signaling apparatus embodying my invention, it is understood that various changes and modifications may be made therein within the scope of the appended claims without departing from the spirit and scope of my invention.

Having thus described my invention, what I claim is:

1. In a railway signal system for a stretch of railway track having an insulated section provided with a pair of conductors extending from one end to the other of said section, a source of direct current connected to one end and a source of alternating current connected to the other end of said conductors respectively, two stick relays, means responsive to traffic on said stretch, means controlled by said traffic responsive means for energizing one or the other of said stick relays according as traffic operates over said stretch in one direction or the other respectively, two control relays one responsive only to direct current and the other responsive only to alternating current, means including a back contact of said one stick relay for connecting said direct current control relay to said conductors at said other end of said section in multiple with said alternating current source, means including a back contact of said other stick relay for connecting said alternating current control relay to said conductors at said one end of said section in multiple with said direct current source, and means controlled by said two control relays for governing traffic operating in either direction through said section.

2. In a railway signal system for a stretch of railway track divided into a plurality of successive adjoining insulated sections including a first, a second and a third section adapted to be traversed in the order named by a train operating in one direction on said stretch, a track circuit for each of said sections, a pair of conductors extending from one end to the other of said second section, a source of direct current connected to one end and a source of alternating current connected to the other end of said conductors respectively, two stick relays one for said third section and the other for said first section, a pick-up and a stick circuit for said one stick relay controlled by the track circuits of said second and said third sections whereby to energize said one stick relay only when a train operates over said stretch in said one direction, a pick-up and a stick circuit for said other stick relay controlled by the track circuits of said second and said first sections whereby to energize said other stick relay only when a train operates over said stretch in the opposite direction, two control relays one responsive only to direct current and the other responsive only to alternating current, means including a back contact of said one stick relay for connecting said one control relay to said other end of said conductors in multiple with said alternating current source, means including a back contact of said other stick relay for connecting said other control relay to said one end of said conductors in multiple

with said direct current source, means controlled by said one control relay for governing traffic operating in said one direction in said section, and means controlled by said other control relay for governing traffic operating in said other direction in said section.

3. In a railway signal system for a stretch of railway track divided into a plurality of successive adjoining insulated sections including a first, a second and a third section adapted to be traversed in the order named by a train operating in one direction on said stretch, a track circuit for each of said sections, a pair of conductors extending from one end to the other of said second section, a source of direct current connected to one end and a source of alternating current connected to the other end of said conductors respectively, means governed by the track circuit of said first section for controlling the polarity of current supplied from said direct current source to said conductors, means governed by the track circuit of said third section for controlling the polarity of current supplied from said alternating current source to said conductors, two stick relays one for said third section and the other for said first section, a pick-up and a stick circuit for said one stick relay controlled by the track circuits of said second and said third sections whereby to energize said one stick relay only when a train operates over said stretch in said one direction, a pick-up and a stick circuit for said other stick relay controlled by the track circuits of said second and said first sections whereby to energize said other stick relay only when a train operates over said stretch in the opposite direction, two control relays one responsive only to direct current and the other responsive only to alternating current, means including a back contact of said one stick relay for connecting said one control relay to said other end of said conductors in multiple with said alternating current source, means including a back contact of said other stick relay for connecting said other control relay to said one end of said conductors in multiple with said direct current source, means controlled by said one control relay for governing traffic operating in said one direction in said section, and means controlled by said other control relay for governing traffic operating in said other direction in said section.

4. A railway signal system for a stretch of railway track divided into a plurality of successive adjoining track sections including a first and a second and a third section traversed in the order named by a train operating in a given direction over said stretch, a track circuit including a track relay for each of said sections, a pair of conductors extending from one end to the other of said second section, a first source of current, a second source of current having characteristics distinctively different from said first source, means controlled by the track relay of said first section for normally connecting said first source to one end of said conductors, means controlled by the track relay of said third section for normally connecting said second source to the other end of said conductors, two directional stick relays, circuit means controlled by the track relays of said second and third sections for energizing one of said stick relays only when a train operates over said stretch in said given direction, circuit means controlled by the track relays of said second and first sections for energizing the

other of said stick relays only when a train operates over said stretch in the opposite direction, two control relays one responsive only to current from said first source and the other relay responsive only to current from said second source, means including a back point of a contact of said one stick relay for normally connecting said one control relay to said other end of said conductors in multiple with said second source and including a front point of said contact for at times connecting said second source to said con-

ductors in an alternate path, means including a back point of a contact of said other stick relay for normally connecting said other control relay to said one end of said conductors in multiple with said first source and including a front point of said contact for at times connecting said first source to said conductors in an alternate path, and signal means controlled by said two control relays for governing traffic operating in either direction in said second section.

HENRY S. YOUNG.
